August W. Rehberger, Brooklyn, N. Y.

Application March 31, 1945, Serial No. 118,802

Term of patent 14 years

(Cl. D34—5)

To all whom it may concern:

Be it known that I, August W. Rehberger, a citizen of the United States, residing at Brooklyn, in the county of Queens and State of New York, have invented a new, original, and ornamental Design for a Dart Game Chart, of which the following is a specification, reference being had to the accompanying drawing, forming a part thereof.

I claim:

The ornamental design for a dart game chart, as shown.

AUGUST W. REHBERGER.
